(57) **CLAIM**

The ornamental design for an operating console for eye testing, as shown and described.

DESCRIPTION

1. Operating console for eye testing

1.1 : Perspective

1.2 : Perspective

1.3 : Front

1.4 : Back

1.5 : Left

1.6 : Right

1.7 : Top

1.8 : Bottom

1.9 : Enlarged

1.10 : Enlarged

1.11 : Enlarged

1.12 : Enlarged

The broken lines shown in the figures depict portions of the operating console for eye testing that form no part of the claimed design; the dot-dash broken lines in figs. 1.1, 1.2, 1.9, 1.10, 1.11, 1.12, and the label "1.9" in fig. 1.1, label "1.10", "1.11", "1.12" in fig. 1.2 are for the purpose of depicting the cut line of the enlarged view and form no part of the claimed design.
